CLAIM

The ornamental design for a self cleaning bidet attachment for toilet, as shown and described.

DESCRIPTION

FIG. 1 is a front view of a self cleaning bidet attachment for toilet design showing my new design.

FIG. 2 is a rear view of a self cleaning bidet attachment for toilet.

FIG. 3 is a left side view of a self cleaning bidet attachment for toilet.

FIG. 4 is a right side view of a self cleaning bidet attachment for toilet.

FIG. 5 is a top view of a self cleaning bidet attachment for toilet; and,

FIG. 6 is a bottom view of a self cleaning bidet attachment for toilet.

Any shading and cross-hatching are not features of the design but are utilized to illustrate the surface contours of the self cleaning bidet attachment for toilet in the drawings.
